UNITED STATES PATENT OFFICE.

NELS R. OLSON, OF BELLINGHAM, WASHINGTON.

LINK-MAKING PRESS.

Application filed September 20, 1924. Serial No. 738,771.

To all whom it may concern:

Be it known that I, NELS R. OLSON, a citizen of the United States, and a resident of Bellingham, in the county of Whatcom and State of Washington, have invented a new and useful Link-Making Press, of which the following is a specification.

My invention relates to improvements in link-making presses, especially the kind which form sawdust, and the like, conveyor links, and the object of my improvement is to provide a simple, direct-acting press which will shape hot iron bars into the desired form and also punch the rivet holes therein while still in the press.

I attain this object with the mechanism illustrated in the accompanying three sheets of drawings, which form a part of this specification, and in which Figure 1 is a plan view of my press, Fig. 2 is a side elevation of Fig. 1, Fig. 3 is a front end elevation of Fig. 1, Fig. 4 is an end elevation of one of the two similar forming blocks drawn on a larger scale, Fig. 5 is a side elevation of Fig. 4, Fig. 6 is a longitudinal view of one of the punch screws with a punch in place therein drawn on a larger scale, Fig. 7 is a plan view of a conveyor link formed in my press, drawn on a larger scale, Fig. 8 is a side elevation of Fig. 7, Fig. 9 is a plan view of one of the pair of press shoes, Fig. 10 is a rear elevation of Fig. 9, Fig. 11 is an end elevation of Fig. 9, Fig. 12 is a plan view of the steam valve used to control the operation of the steam piston drawn on a larger scale, Fig. 13 is a front side elevation of Fig. 12, Fig. 14 is a rear side elevation of Fig. 12, Fig. 15 is a plan view of said valve with its cap removed, Fig. 16 is a front side elevation of Fig. 15 with the valve housing in section on a vertical medial plane, Fig. 17 is a rear side elevation of Fig. 15 with said valve housing in section on a medial vertical plane, Fig. 18 is a side elevation of the shape block, drawn on a larger scale and Fig. 19 is a plan view of Fig. 18.

Similar characters refer to similar parts throughout. Certain parts are broken away to show other parts hidden thereby.

More particularly: The top surface of table top 20 is in four levels which, beginning at the front and higher end, are designated as a^{20} , b^{20} , c^{20} and d^{20} . Legs 21 provide supports for said table top. Shape block 22 is centrally placed, transversally,

on top of surface a^{20} and is a rigid part of the table top. Said shape block is of rectangular form excepting the rear ends of the sides each of which are cut away at 60 a^{22} , a^{22} . A vertical hole b^{22} is made in each corner of block 22 entirely through the same. A horizontal hole c^{22} is made in the vertical middle of each side of said block to intersect holes b^{22} . Holes c^{22} are shearing holes 65 for punches while holes b^{22} allow the discs punched into holes c^{22} to fall therefrom. To transverse crosshead 23 is bolted slides 69 a^{23} , a^{23} , each of which is movable horizontally in one of slideway slots 24 longitudinal- 70 ly in table top 20. Crosshead 23 has a notch b^{23} centrally in the forward edge thereof. Two rollers 25 are mounted on vertical pins 75 for revolution on crosshead 23. Two forming fingers 26 are mounted for horizontal oscillation on pins a^{26} in crosshead 23 equidistant from the longitudinal center thereof and project forward therefrom. Each of fingers 26 has a boss b^{26} on the inner side thereof at its rear end. Fingers 26 are located to lie one on either side of block 22 at a distance therefrom equal to the thickness of the iron bars from which the links are formed. Steam cylinder 27 is fastened centrally to the table top on level d^{20} and extends longitudinally thereof. Its piston rod 28 is fastened to a piston a^{27} therein, and also centrally to the rear side of crosshead 23. The reciprocation of said piston in said cylinder causes crosshead 23 to move forth 80 and back from its foremost position at 23' to its most rearward position at 23''. Steam valve 29 is used to control the operation of said piston a^{27} in cylinder 27. Steam enters 85 said valve through pipe 30 and passes through valve cylinder a^{29} in hole 36 to enter vertical groove a^{30} in the rear wall of said cylinder. When valve handle 36, see Fig. 1, is in its illustrated middle position no steam can pass said valve. But when said handle 90 is moved to L steam enters horizontal groove a^{30} , in the front wall of cylinder a^{29} , passes through hole 36 and enters pipe 33 from the groove a^{30} . Pipe 33 conducts steam into cylinder 27 in front of its piston which it 95 forces to the rear thereof moving crosshead 23 rearward. Meanwhile the air or steam in said cylinder to the rear of its piston leaves through pipe 32 and enters hole 34 in the valve cylinder whence it passes into 100 horizontal slot a^{31} in the front wall of a^{29} and enters exhaust pipe 31. Then by turn-

ing handle 36 to position R steam pipe 30 is connected to pipe 32 and steam enters said cylinder behind said piston and forces it forward moving crosshead 23 forward also 5 toward its position at 23'. Meanwhile steam from in front of said piston leaves the cylinder through pipe 33 and enters hole 35 in cylinder a^{29} whence it passes into horizontal groove a^{31} and enters exhaust 10 pipe 31. Thus with valve 29 crosshead 23 can be moved forth and back longitudinally of table 20 and stopped wherever desired. Two right and left press shoes 27 are each pivoted on one of pins 38 in table plane a^{20} 15 for horizontal oscillation on said pivots 38. These shoes are located to lie a link-bar's thickness from the sides of shape block 22 when their press surfaces are parallel with said block's sides, except that opposite recessions a^{22} are corresponding recessions e^{37} in each of said shoes. These will be again referred to. The upper surfaces of shoes 37 are slightly higher than the corresponding surface of shape block 22 and said shoe 20 surfaces continue to the rear ends of the shoes at a^{37} where they are cut away down to the level of table plane a^{20} for reasons hereinafter explained. At the rear end of each of shoes 37 is handle 39 the outer edge 25 of which has three intersecting planes a^{39} , b^{39} and c^{39} . Plane surface a^{39} is, by construction, parallel with guide slots 24 when shoe 37 is in its illustrated full-line position, surface b^{39} is, by preference, inclined 30 at an angle of about 45° when said shoe is in said position, while surface c^{39} is parallel with said guide slots when said handle is in its dotted-line position at 39'. Each of rollers 25 is located on crosshead 23 to bear 35 upon both surfaces a^{39} and b^{39} of one of said handles when the same is in its full-line position. When passing from its full-line position to its dotted-line position at 23' crosshead 23 carries said rollers 25 in contact with surfaces a^{39} without moving shoe 37. As soon as rollers 25 pass the intersections of plane surfaces b^{39} and c^{39} while crosshead 23 is moving toward its position 40 23'' said rollers cease to move said shoes on their pivots. But while said rollers 25 are moving rearward over surfaces b^{39} handles 39 are carried to their dotted-line positions at 39' and shoes 37 are brought nearest to shape block 22. In the outer side of 45 each of shoes 37 is a rectangular recess b^{37} in the end walls of which are slideways c^{37} and d^{37} , see Fig. 10. In said slideways in each of said shoes is mounted punch crosshead 40, retained in said slideways by caps 41. Pin a^{40} in said crosshead 40 pivotally connects link 42 thereto. The outer end of link 42 is connected to pair of links 43 by pivot bolt a^{42} . Said pair of links 43 is pivotally mounted on table 20 by pin a^{43} . Stop screw 44 is engaged in a boss on said table

to bear on lower link 43 and limit its forward swing. Each of said lower links 43 is provided with a similar stop screw 44. The rear end of each of tension spiral springs 45 is fastened to the lower of each of pairs 70 of links 43 and the forward end thereof is fastened on top of boss 46 on said table top. Said springs 45 react to retain links 43 and 42 in their illustrated full-line positions. The rear ends of bars 47, 47 are connected 75 to crosshead 23 by pivot bolts a^{47} , a^{47} . The front end of each of said bars has longitudinal slot b^{47} therein which is engaged with pivot bolt a^{42} . Slot b^{47} terminates at a point 80 at its forward end which will cause bars 47 to draw links 42 and 43 rearward to dotted positions 42' and 43' respectively when crosshead 23 has reached its position at 23''. This movement rearward of links 42 and 43 is caused only while rollers 25 are moving 85 over surfaces c^{39} on handles 39, and it causes punch crossheads 40 to move toward each other in shoes 37 till said crossheads are proximate to the bottoms of recesses b^{37} . In each of crossheads 40 are engaged two 90 screws 48. These screws each have a threaded body next the head of larger diameter, which is engaged with tapped holes in said crossheads, and a smooth body b^{48} of smaller diameter, see Fig. 6. Body b^{48} is adapted 95 to reciprocate in one of holes g^{37} in one of shoes 37, see Fig. 10. In the end of body b^{48} is engaged punch 49, see Fig. 6, adapted to reciprocate in one of holes h^{37} , see Fig. 10, and also in one of holes c^{22} , see Fig. 18. 100 Body b^{48} enters deep enough in shoe 37 to cause punch 49 to enter shape block 22 as far as holes b^{22} when links 42, 43 are in their dotted line position. Two form blocks 50 are each reciprocable in a vertical hole 105 through the table adjacent each corner recess a^{22} in shape block 22. Blocks 50 can each rise even with the top of shape block 22 in which position holes a^{50} therethrough are in line with holes c^{22} rearward in block 22. Blocks 50 each have a longitudinal channel b^{50} in their facing sides. Each of said blocks also has a hole c^{50} near its lower end. In holes c^{50} are engaged the ends of 110 rod 51 which rigidly fastens said blocks together. Bar 52 is fastened to slide blocks a^{23} beneath table 20 to be parallel with crosshead 23. To bar 52 is fastened the rear end of runner 53 which has longitudinal cam slot 54 therein. The ends of cam slot 54 are horizontal and straight but on different levels and are joined by incline a^{54} . Runner 53 is further supported by 115 guide bracket 55 which is fastened to the bottom of table 20 and through which said bar is reciprocable. Before fastening to blocks 50 rod 51 is mounted in cam slot 54. This slot is so placed that when rod 51 is in the rear end thereof blocks 50 are flush with the table plane a^{20} , when said rod is in the 120

forward end of said slot said blocks are flush with the top of block 22. When runner 53 moves rearward from its illustrated full-line position to its dotted-line position 5 at 53" inclined slot a^{54} causes rod 51 to rise to the upper part of the cam slot which retains said rod and blocks 50 in their upper position with the tops of said blocks flush with the top surface of block 22. When said 10 runner moves from position 53" to 53 rod 51 and blocks 50 are forced to their lower positions with the tops of said blocks flush with table plane a^{20} just before the end of said movement. Also said blocks 50 remain 15 in their lower position during the movement of said runner from position 53 to position 53' forward. Stud 57, see Fig. 1, projects vertically upward from table plane a^{22} to the rear of the middle of shape block 22 and the top thereof is normally flush with the top of said block while the space between said block and stud is the thickness of the bars to be formed into links. The 20 lower end of stud 57 is central in rod 56 which is reciprocable in a vertical hole through the table top. Rod 56 protrudes beneath said table top and its lower end is fastened to plate 59. The upper end of rod 56 is flush with table plane a^{20} when the top 25 of stud 57 is flush with the top of block 22. Studs 58, 58 are reciprocable in vertical holes through the table top midway of the sides of block 22 and adjacent thereto. Normally the top end of studs 58 are flush with table plane a^{20} . Studs 58 are central in the 30 upper ends of rods a^{58} beneath the table. The lower ends of rods a^{58} are fastened to plate 59. Plate 59 bears on the inner end of pedal 60 which is fulcrumed on pin 61 in a floor bracket. And when said plate is 35 in its lower position, shown in full lines at 59, it also bears on top of said pedal lever over said bracket which stops its further downward movement. When at this position 40 the upper end of stud 57 is flush with the top of block 22 and the upper ends of studs 58 are flush with table plane a^{20} . Pressure downward on the outer end of pedal 60 causes plate 59 to rise to its upper position 45 at 59' and carries the upper end of rod 56 and the upper ends of studs 58 to be flush with the top of block 22. 50

In operation: Assuming the movable parts of the machine in the illustrated full-line positions. A heated bar of mild steel of suitable dimensions is placed in the machine edge up between the rear end of shape block 22 and stud 57 with its middle at said stud. This bar is not shown in place 55 in the illustrations because of the closeness of the lines required to show parts of the machine. Valve handle 36 is turned to L and crosshead 23 and fingers 26 are driven forward to dotted-line positions at 23'. Said fingers 26 force a fold in the hot bar 60 on both sides of block 22 between said block and the surfaces a^{37} , a^{37} of shoes 37 and continue to move forward till they and the newly-formed folds in the hot bar completely fill the triangular space on each side 65 of block 22 between shoes 37, 37. Also bosses b^{26} on said fingers force said hot bar to conform to the shape of the shape block at recesses a^{22} , a^{22} therein. During this forward movement of crosshead 23 rollers 25 70 have maintained bearing on surfaces a^{39} , a^{39} of arms 39 thus preventing shoes 37, 37 from swinging outward. The folded position of said hot bar is shown in dotted lines in Fig. 1. The said forward movement of crosshead 23 also carried bars 47, 47 forward to their dotted positions at 47', 47'. But slots b^{47} , b^{47} in said bars extend far enough rearward to prevent the said 75 forward movement of said bars from exerting pressure on knuckle joints 42, 43-42, 43. During the forward movement of crosshead 23 runner 53 also was carried forward to position 53', see Fig. 2; but, since rod 51 remained in the lower level of slot 54 80 of said runner, form blocks 50, 50 were retained in their lower position with their upper ends flush with the table top, as shown in Figs. 2 and 18. Steam valve handle 36 85 is now swung to R and crosshead 23 is moved rearward. Directly after crosshead 23 passes its position at 23 the inclined portion a^{54} of runner slot 54 forces form blocks 50, 50 upward, and when rod 51 90 enters that part of said runner slot on the upper level said blocks 50 have reached a point where their upper ends are flush with the top of shape block 22, and here they remain till said crosshead again approaches its position at 23 from the rear. Said crosshead 95 proceeds rearward till rollers 25, 25, while traversing inclines b^{39} , b^{39} have swung arms 39, 39 toward each other and caused shoes 37, 37 to swing toward each other on pivots 38, 38, gradually closing the folds in 100 said hot bar between said shoes and the shape block until said folded over ends lie flatly on each other and are strongly pressed together by the time rollers 25, 25 reach surfaces c^{39} when said arms cease to swing. 105 By this time the front end of slots b^{47} have reached pins a^{42} , a^{42} and knuckles 42, 43-42, 43 have reached their dotted-line positions 110 at 42', 43'-42', 43' which forced crossheads 40, 40 to their nearest approach and pressed punches 49, 49, 49, 49 through the bifoldded sides of the newly shaped link 62. While the punches in the forward ends 115 of shoes 37, 37 pass through two thicknesses of the link bar which lie close together the punches in the rear ends of said shoes must first pass through the offset ends of the bar lying against form blocks 50 and then, after passing through said form blocks, must go further and pass through the inner folds 120 125 130

and enter shape block 22. While passing through holes a^{50} in blocks 50 the punched-out discs have an opportunity to leave the ends of the punches and drop downward 5 through channels b^{50} in said form blocks. Now the new link is completely shaped and the required rivet holes have been made therein. Handle 36 of steam valve 29 is now turned to L and crosshead 23 and all 10 attachments thereto are returned to their full-line positions which leaves the new link lying in place about shape block 22. In order to raise the link to a position where it is accessible for grasping with tongs, downward pressure is applied to pedal 60 by 15 the operator standing near valve 29 and rod 56 and studs 58, 58 are raised to positions 56' and 58', 58' respectively. This upward movement of this rod and studs carries the new link above the level of shape block 22 where it is readily accessible. Now the machine is ready for another hot bar on which the work can be done in the order above recited.

Having thus disclosed my invention, what I claim as new and desire to secure by Letters Patent is,—

1. In a machine of the character described in combination, a shape block, a pair of 30 press shoes one pivoted for oscillation on each side of said shape block, a pair of reciprocable press fingers one adapted to enter each triangular space producible between each of said oscillatable press shoes and the 35 sides of said shape block, and a reciprocable prime mover adapted to separately reciprocate said press fingers and oscillate said press shoes whereby a link bar set against one end of said shape block is looped by 40 said press fingers in said triangular spaces and then folded against said shape block sides by said press shoes.

2. In a machine of the character described in combination, a shape block having die 45 holes in the two sides thereof, a pair of press shoes one pivoted on each side of said shape block for oscillation, punches mounted in said press shoes for reciprocation adapted to enter said die holes in said shape block 50 when said press shoes are adjacent thereto, a pair of reciprocable press fingers one adapted to enter each triangular space producible between each of said press shoes and said shape block sides, and a reciprocable 55 prime mover adapted to separately recipro-

cate said press fingers, oscillate said press shoes and reciprocate said punches whereby a link bar set against one end of said shape block is looped by said press fingers in said triangular spaces, folded against said shape 60 block sides by said press shoes and perforated by said punches.

3. In a machine of the character described in combination, a shape block having die holes in the sides thereof, a pair of oscillatable press shoes pivoted one on each side of said shape block, punches mounted for reciprocation in said press shoes adapted to enter said die holes when adjacent said shape block, and further adapted to pass through 70 die holes in form blocks, a pair of reciprocable press fingers one adapted to enter each triangular space producible between each of said press shoes and said shape block sides, a pair of form blocks having die holes there-through registrable with said die holes in said shape block when in operative position and said blocks mounted for reciprocation in holes a link-bar thickness from said 75 shape block sides, and a reciprocable prime mover adapted to separately reciprocate said press fingers, reciprocate said form blocks, oscillate said press shoes, and reciprocate said punches.

4. In a machine of the character described in combination, a shape block having die holes in the two sides thereof, a pair of press shoes one pivoted for oscillation on each side of said shape block, punches mounted for reciprocation in said press shoes adapted to enter said die holes in said shape block and further adapted to pass through die holes in form blocks when in operative position, a pair of reciprocable press fingers one adapted to enter each triangular space producible 90 between said press shoes and said shape block, a pair of form blocks mounted for reciprocation in holes a link-bar thickness from said shape block sides having die holes therethrough registrable with said shape 95 block die holes when in operative position, a reciprocable prime mover adapted to separately reciprocate said press fingers, reciprocate said form blocks, oscillate said press shoes and reciprocate said punches, a plurality of studs mounted for reciprocation in holes adjacent the said sides and one end of said shape block, and a pedal adapted to reciprocate said studs by foot power.

NELS R. OLSON.
